(Cl. D44—29)

To all whom it may concern:

Be it known that I, Arthur L. Barney, a citizen of the United States, residing in the city of New York, county and State of New York, have invented a new, original, and ornamental Design for a Child's Spoon or Analogous Article, of which the following is a specification, reference being made to the accompanying drawing, forming a part thereof.

I claim:

The ornamental design for a child's spoon or analogous article, as shown.

ARTHUR L. BARNEY.
